UNITED STATES PATENT OFFICE.

JOHN BRANDWOOD, THOMAS BRANDWOOD, AND EDWARD BRANDWOOD, OF BURY,
ENGLAND.

APPARATUS FOR TREATING TEXTILE FIBERS WITH LIQUIDS AND GASES.

1,101,248.

Specification of Letters Patent. Patented June 23, 1914.

Application filed July 31, 1913. Serial No. 782,205.

To all whom it may concern:

Be it known that we, JOHN BRANDWOOD, THOMAS BRANDWOOD, and EDWARD BRANDWOOD, all subjects of the King of Great Britain and Ireland, and all residents of Bury, in the county of Lancaster, England, have invented certain new and useful Improvements in Apparatus for Treating Textile Fibers with Liquids and Gases, of which the following is a specification.

This invention relates to apparatus in which cops or the like may be first treated with liquid as in dyeing or bleaching and may then be treated without removal with any suitable gases or vapors.

Apparatus constructed according to this invention comprises a keir or other like closable vessel divided into upper and lower compartments by a partition. The two compartments thus formed are of unequal capacities and are of such capacities and the quantity of liquid employed is such that while the upper chamber during the liquid treatment process will be full of or contain liquid at any desired pressure when the apparatus is working to force the liquid through the cops or the like which are placed upon the upper surface of the partition, such liquid can all be contained in the lower compartment and its connected pump or the like with space to spare when the liquid treatment has ceased, and this without the provision of any storage tanks extra to the apparatus. When the liquid treatment has ceased and the liquid is contained in the lower compartment the cops can then be treated by air or other gases or the like while still in the positions which they occupied for liquid treatment. By a reference to cops is to be understood also the inclusion of other forms of yarn and fibers wound upon perforated bobbins or the like.

The improved apparatus is illustrated in one form in the accompanying drawings.

Figure 1 illustrates the apparatus in elevation, part of the keir shell being broken away to give a view of the interior. Fig. 2 is a half plan and half horizontal section taken above the level of the partition already referred to. Fig. 3 is a vertical sectional view of a detail.

Referring to the drawings, A is an approximately vertical cylindrical keir closed

at its bottom and furnished with a removable cover B at its upper end.

C is a horizontal partition dividing the keir into upper and lower compartments D, D¹. The partition C is formed with a number of holes E and in each hole may closely fit a plate F carrying perforated spindles bearing cops G, the open ends of the perforated spindles coming to the under faces of the plates F. When each hole E has its plate F in place then communication between the upper and lower compartments D, D¹ inside the keir can only be through the perforated spindles and the fibrous matter borne by them. The use of such spindles is of course well known in cop dyeing.

H is a centrifugal pump; J a pipe, and J¹ branches thereof by means of which dye or other liquor is forced from the pump into the upper compartment D; and K is a pipe from the bottom of the lower compartment D¹ to return liquid from such compartment to the pump.

L is an air inlet pipe opening into the upper compartment and M is an air outlet or suction pipe leading from the upper part of the lower compartment. Instead of air, other gases or vapors may be used, but they will be included in a general reference to air.

When the apparatus is to be used plates F bearing cops are inserted through the open upper end of the keir until all the holes E in the partition are filled by them. The cover B is then screwed down into place to close the upper compartment. The pump H is then set going and liquid is forced from the pump into the upper compartment. There is sufficient liquor in the circulating system to completely fill the upper compartment, but not sufficient to fill the lower and larger compartment by several inches. The pressure in the upper compartment continually forces liquid through the fibers of the cops and the perforated spindles, which liquid falls into the lower compartment and returns to the pump by which it is again sent to the upper compartment.

During this liquid treatment the air pipe M may be open but the pipe L will be closed. When the liquid treatment is finished and the pump stops, any liquid which is left in the upper compartment runs down into the lower compartment. It may do this through the branches J¹ which are set with

the lower portions of their channels level with the upper face or even slightly lower than the upper face of the partition C, and through the pipe J, the pump H, and 5 pipe K. Or drainage from the upper compartment to the lower may be by means of a plug outlet or equivalent formed in the partition. When the liquor has run out of the upper compartment and is say standing at 10 about the level $x-y$ in the lower compartment (lower than the opening of the pipe M) the treatment with air or gas may commence and will be in the same direction as the treatment with liquid, that is from above 15 downward.

The air treatment may be by suction of air through the pipe M, air being admitted either through the pipe L or through the opened 20 cover of the keir; it may be by forced passage of air which is admitted to the upper compartment D under pressure through the pipe L when the cover of the keir is closed. With air under pressure the pipe M would be the escape pipe. The air compressing or 25 suction appliances are not shown in the drawings. They may be of any usual construction.

It is for treatment with air under externally applied pressure that the apparatus 30 is particularly suitable. The air should be supplied under such a heavy pressure and in such volume as to insure that air passes through the substance of the various yarns or the like and not merely through the interspaces between them.

Fig. 3 shows how the plates F may be simply dropped in place in the holes E in the partition C and will seal themselves against pressure from above. The edge of each 40 plate has a downwardly depending flange f which comes upon a rubber or like packing ring e placed in a seat surrounding the hole E. The weight of the plate and the pressure of liquid or air from above makes a 45 tight joint. The plates are easily lifted out when the cover of the keir is lifted.

What we claim is:—

1. Apparatus for first treating cops with liquid and then treating them with air without removing them, such apparatus comprising a keir, a transverse partition therein for bearing the cops and dividing the keir into upper and lower compartments of which the lower is the larger, a liquid circulating pump and its pipes, air and liquid inlets to the upper compartment, and air and liquid outlets in the lower compartment, substantially as set forth. 50

2. Apparatus for first treating cops with liquid and then treating them with air without removing them, comprising a keir, a transverse partition therein for bearing the cops and dividing the keir into upper and lower compartments of which the lower is the larger, a circulating pump and its pipes, 55 air and liquid inlets to the upper compartment, a liquid outlet at the bottom of the lower compartment and an air outlet situated in the upper part of said lower compartment, substantially as set forth. 60

3. Apparatus for first treating cops with liquid and then treating them with air without removing them, such apparatus comprising a keir, a transverse partition therein dividing the keir into upper and lower compartments of which the lower is the larger, seated holes formed in such partition, cop carrying plates to seat themselves around such holes, a liquid circulating pump and its pipes, air and liquid inlets to the upper compartment, and air and liquid outlets in the lower compartment, substantially as set forth. 70

In witness whereof we have hereunto set our hands in the presence of two subscribing witnesses. 75
